UNITED STATES PATENT OFFICE

168,687

FRONT FOR A WALL OVEN

Arleigh G. Hupp, New Albany, Ind.

Application January 2, 1952, Serial No. 17,897

Term of patent 14 years

(Cl. D81—25)

To all whom it may concern:

Be it known that I, Arleigh G. Hupp, a citizen of the United States, residing at New Albany, in the county of Floyd and State of Indiana, have invented a new, original, and ornamental Design for a Front for a Wall Oven, of which the following is a specification, reference being had to the accompanying drawing, forming part thereof.

The figure is a perspective view of a front for a wall oven embodying my new design.

The characteristic features of my design are shown by means of full lines.

I claim:

The ornamental design for a front for a wall oven, as shown and described.

ARLEIGH G. HUPP.
